UNITED STATES PATENT OFFICE

2,574,463

T-SQUARE SECURING MEANS

Harold Addison Chapin, San Jose, Calif.

Application December 23, 1946, Serial No. 717,875

2 Claims. (Cl. 33—76)

1

The present invention relates to means for holding the head of a T square firmly and slidably against the side of a drafting-board when in use.

As heretofore made the T square is held in contact with the board by pressure of the hand and sometimes will be allowed to slide inadvertently over a line previously made in ink and still fresh, in such a manner as to smear the ink and ruin the drawing.

One object of the invention is to provide a device that can be easily and quickly attached to the board and square that will effectually prevent its accidentally slipping and hold the blade of the square at right-angles to the board.

Another object of the invention is to provide resiliently controlled means for holding the square in position and instantly released for permitting the easy manipulation of the square on the board and at the same time prevent the tipping of the square on the board.

It is also an object of the invention to provide a device of the character indicated that can be easily manipulated by the fingers of one hand.

In the drawing:

Figure 1 is a top plan view of my invention as attached to a square and positioned on a board, parts being broken away.

Figure 2 is an enlarged sectional view on line 2—2 on Figure 1.

Figure 3 is an enlarged top plan view of my invention as arranged on a T square.

Figure 4 is a bottom plan view of a square in position on a board, parts being broken away, and embodying my invention.

Figure 5 is a cross sectional view on the line 5—5 of Figure 2.

Referring now more particularly to the drawing, I show at 1 a drafting board fitted on one edge with a strip of metal 2 to act as a smooth and true edge for the T square to slide on, this metal strip being slightly wider than the thickness of the blade head 4 of the T square in conjunction with which it is used. The opposite edge of the board is fitted with a strip of metal 3, this latter strip being in the form of an angle bar, and placed with its top surface lying flush with the top surface of the board as shown.

The head of the T square, as mentioned, is shown at 4 with the blade showing at 5, the head end of the blade having a sheet of sheet metal 6 bent thereover as shown to provide clearance for the blade on the board and permit its sliding freely thereover, and to provide a sliding surface for the member hereinafter described.

2

Passing through the blade head 4 and overlying end of blade 5 is a bolt 7 supporting a knob 8 in fixed relation to the blade head 4 and blade 5, the said knob 8 having a groove 9 formed in its bottom end to permit the strap 10 to slide therethrough.

The strap 10 is a flat strip of sheet metal lying flat on the top surface of the blade 5 in parallel relation therewith and along its median line, 10 passing through the groove 9 and terminating in a strap head 11. The head 11 is a heavy piece of sheet-metal bent into a U-shape when viewed endwise, the space between the top and bottom leaves of the U-shaped member being somewhat 15 greater than the thickness of the strap 10 which it encompasses and to which it is bolted as at 12. In this space between the top and bottom leaves of the U-shaped member is placed a spring 13 with one end bearing against the member and the other end bearing against the adjacent edge of 20 the metal member 6. Disposing the spring 13 in this manner enables it to urge the strap head 11 and consequently the strap 10 outwardly with respect to the blade 5.

The strap 10 has a slot 14 formed therein through which the bolt 7 passes and which permits the strap to slide on blade 5. Adjacent the free end of blade 5 is bolted as at 15 a shoe 16, a slot 17 in blade 5 allowing the bolt 16 to slide backwards and forwards in the blade, the shoe 30 16 being supported below the blade 5 to have sliding engagement with the angle bar 3.

Normally the spring 13 urges the shoe 16 against the angle bar 3 below its top flange and thus holds the blade head 4 snugly against the metal strip 2 and holds the T square firmly in position. By hooking the thumb of the left hand around the knob 8 the fingers of that hand may be freely 35 used to press upon the strap head 11 and so release the spring pressure forcing the shoe 16 into 40 contact with the metal strip 3 and permitting the free movement of the blade 5.

The slots 14 and 17 permit the strap 10 to be moved lengthwise of the blade 5 for releasing the pressure against strip 3, and also to permit the 45 pressure of spring 13 to return that pressure instantly when so desired by the operator.

Two guide members, preferably resilient, are shown at 18—18 fastened to the underside of the metal strip 2 to pass under and bear against the bottom front edge of the head 4. These guide members operate to hold the blade head 4 in its proper relation to the top surface of the drafting board, that is, in most cases with its top surface aligned flush with the top surface of the 50 board.

It is to be noted that the sheet metal strip 6 which is disposed over the head end of the blade 5 provides reinforcing bearings spaced in the direction of the length of the bolt 7 to aid in sustaining the same when the T-square is actuated by the knob 8.

In the manner described the T-square may be instantly adjusted along the length of the board and yet at all times it is held against accidental movement.

Having thus described my invention, what I claim as new and desire to secure by Letters Patent, is:

1. The combination of a T-square including a blade, and a transversely extending head secured to one end thereof and having a straight inner wall for engagement with the edge of a drafting board, a U-shaped holder of relatively thin stock carrying the head end of the blade, one leg of the U-shaped holder being disposed between the T-square head and the blade whereby to space the latter slightly above the plane of the top of a drafting board, an elongated bolt extending through said head, blade and blade holder; a knob mounted on the projected end of said bolt above said blade and head, an elongated flat metal strap extending lengthwise of said blade, one end of said strap normally projecting beyond the outer edge of said head and having a down-turned portion disposed in opposition to the outer edge of said head, said strap having a lineal slot through which said knob-carrying bolt extends, a vertically extending pin secured to the strap adjacent its other end, the blade having a slot through which said pin extends to a point below the undersurface of said blade, a shoe carried by the lower end of said pin and positioned to engage the edge of the drafting board opposite to that engaged by the T-square head, said knob having a groove in its

bottom surface through which said strap is adapted to slide, and spring means interposed between the down-turned end of said strap and the rear edge of said blade and its U-shaped holder.

2. The combination of a T-square including a blade, and a transversely extending head secured to one end thereof and having a straight inner wall for engagement with the edge of a drafting board, an elongated bolt extending through said head and blade and projecting above the top surface of the latter, a knob mounted on the projected end of said bolt above said blade and head, an elongated flat metal strap extending lengthwise of said blade, one end of said strap normally projecting beyond the outer edge of said head and having a down-turned portion disposed in opposition to the outer edge of said head, said strap having a lineal slot through which said knob-carrying bolt extends, a depending drafting board-edge-engaging shoe element carried by said strap at the end remote from the knob, said blade and strap having cooperating guide means adjacent said last mentioned end of said strap.

HAROLD ADDISON CHAPIN.
